C. ELLIS ET AL.

APPARATUS FOR TREATING FILMS

Filed March 12. 1924

UNITED STATES PATENT OFFICE.

CARLETON ELLIS AND HARRY M. WEBER, OF MONTCLAIR, NEW JERSEY; SAID ELLIS
ASSIGNOR TO ELLIS-FOSTER COMPANY, A CORPORATION OF NEW JERSEY.

APPARATUS FOR TREATING FILMS.

Application filed March 12, 1924. Serial No. 698,678.

This invention relates to apparatus for treating moving picture film and other photographic film to remove the emulsion therefrom whereby the silver contained 5 therein may be recovered and the nitrocellulose film basis utilized in various ways.

The apparatus involves primarily means allowing a continuous method of feeding film such as used moving picture film 10 through a zone where it is subjected to a moistening treatment, preferably an alkaline solution preferably hot in order to soften and dislodge the gelatin coating and after the latter has been suitably removed by rubbing, brushing, squeezing or similar treatment, washing off any of the alkaline material which may have been used as the softening liquid and thereupon drying such film, the entire operation preferably being 15 conducted continuously under conditions minimizing the fire risk or hazard to a substantial degree.

The invention will be illustrated by reference to the appended drawing which shows 20 in vertical section an apparatus which is adapted for carrying out the foregoing process. In the drawing 1 is the film, 2 being the shaft on which the reel of film to be cleaned is mounted. 3 is a steel magazine 25 having a hinged cover 4 and safety rollers 5. 6 is a guide roller, 8 is a movable guide roller having tripping arm 7, 39 being shaft on which tripping arm is mounted. 12 is a tank or vat containing the aqueous softening liquor 14 which is heated by means of coils 38. 9 is a movable agitator geared to a stationary agitator 11 having a tripping arm 10. Stationary agitator 11 is operated by means of motor 30 mounted on frame- 30 work of apparatus 31. 13 and 15 are guide rollers. 16 is a vat or trough for catching the wash waters having outlet 39. 17 and 18 are wash water jets. 19 is a guide roller. 20 is a wringer roll for removing excess of 35 moisture from the wet film having tripping arm 21 and tension adjusting nut and bolt 32. 22 is a hot box having steam coils 23. 24 is a guide roller. 25 is the reel of cleaned film mounted on shaft 26. 27 is a steel magazine having hinged cover 28 and safety rollers 29. 33 is a motor for driving reducing gears 35 by means of driving belt or chain 34 which in turn drives the take-up reels and wringer rolls by means of driving belts 40 or chains 36 and 37. The driving mechanism 45

as shown in the drawing is for illustration purposes only as any suitable method or means may be used for this purpose.

In the operation of the apparatus as illustrated in Figures 4 and 5 film to be 50 cleaned is mounted on shaft 2 in one of the magazines as shown in the drawing. The film is fed through the safety rolls 5 over guide roll 6. In order to eliminate the necessity of passing the film under the guide roller 65 8 and movable agitator 9 while they are immersed in the hot feeding medium, the roller and agitator are raised by means of the tripping arms 7 and 10 clear of the solution. The film is then passed over guide roller 70 13, under guide roller 15 between wash water jets 17 and 18 through wringer rolls 20, through hot box 22, under guide roller 24 through safety rollers 29 and attached to the take-up reel. The caustic soda solution 75 is first heated to 85-90° C. the film lowered into the hot solution by raising the tripping arm and the movable agitator dropped into place. The covers of both magazines are then closed and the film is then passed slowly by means of suitable driving device 80 through the various steps of the process. The agitator is then revolved at about 400 R. P. M. and in this manner the hot aqueous alkaline solution is thrown against the surface of the film removing the silver containing emulsion. The film then passes on to the wash water jets where it is washed free 85 of any caustic liquors which may have been carried by the film mechanically, the waste wash water passing into the wash water receiving tank. The wash water being preferably hot in order to prevent coagulation and thereby interfere with the removal of any small quantity of gelatin which may 90 have adhered to the film. The film then passes through wringer rolls 20 where the greater proportion of moisture is removed. It then passes through the hot box where any moisture remaining on the film is removed by evaporation, and then passes 95 through the safety rollers onto the take-up reel. When the supply of film to be cleaned on the first reel is almost exhausted a fresh supply of film is placed in the second magazine and is attached to the end of the film from the first magazine by any suitable means such as clips, film cement etc. In this manner the necessity of re-threading the film over the various rolls and thereby preventing 100 105 110

the continuity of the process is overcome. The shaft on which the exhausted reels of film were mounted is recharged with additional reels of film to be cleaned and these 5 in turn attached to the end of the reels of film in the second magazine as fast as they become exhausted. On the take up side of the apparatus, as the reels become of any desired size the film is cut and attached to 10 the second take up reel. The shaft upon which the filled take-up reels are mounted is removed from the magazine, the cleaned film removed from the shaft and the shaft replaced in the magazine ready for the film 15 to be attached when the reels of film on the second shaft have attained the desired size.

In case the film outside of the magazine is accidentally ignited through any cause whatsoever the safety rollers 5 and 29 prevent 20 the film from burning back to the feed or take-up reels and as an added precaution a sprinkler system (not shown) for drenching the reels in the magazine may be provided. In this manner the fire risk or hazard 25 is minimized inasmuch as only the film which might be passing from the feed magazines to the alkaline softening liquor and that film passing from the wringer through the hot box to the take-up magazine could 30 burn.

By constructing the hot box of steel which is suitably heat-insulated by means of any suitable insulating material the fire risk could be further reduced. We do not wish 35 to limit ourselves to the use of a hot alkaline solution as the emulsion can also be removed by the use of steam, boiling water, a hot salt solution, a hot acid solution etc. We have found however that in using boiling 40 water or steam there is a certain amount of shrinkage of the film depending upon the length of time that the film is subjected to the high temperature involved by the use 45 of boiling water which is objectionable when the film is to be resensitized and used for the manufacture of motion picture film. However, when the film is to be used for other purposes such as lacquers, artificial leather coatings etc. the shrinkage of the 50 film is immaterial.

The foregoing application contains subject matter common to our copending application Serial No. 522,915.

The foregoing description involves many 55 details but such explicit description should not be interpreted as a limitation with respect to the subject matter of the present invention. The latter broadly speaking is for

apparatus for stripping the emulsion from moving picture film or other celluloid or 60 analogous film which apparatus comprises a receptacle adapted to contain an aqueous medium or means for applying such aqueous medium which preferably is heated, means for progressively moving the film through 65 such medium or into contact with such medium whereby the emulsion is softened and scrubbing device or other means for removing the softened emulsion. The apparatus preferably includes means for washing and 70 drying the stripped film.

It should be noted that the present invention enables films to be stripped in what may be termed a continuous manner, that is while the film is in motion and continuously advancing it is subjected to a series of operations designed to soften, scrub and dry the film so that the operation has a substantial degree of continuity. This is in contrast to any method whereby a bulky mass of film is 80 thrown into a tank, boiled with water to soften and remove the emulsion, washed and dried in batches. In the present invention one end of a long roll of film may be started through the apparatus and the film feeding 85 from the roll will progress continuously through the apparatus and be treated continuously and successively in the manner aforesaid.

What we claim is:—

1. Apparatus for stripping the emulsion from celluloid film which comprises a receptacle adapted to contain an aqueous stripping medium, means for heating said medium, means for continuously passing the film through such heated medium whereby the emulsion is softened, means for removing the softened emulsion and means for washing and drying said film. 90

2. Apparatus for stripping moving picture film comprising a receptacle adapted to contain an aqueous medium, means for progressively moving said film through such medium whereby the emulsion of said film is softened, means for removing the softened 105 emulsion, and means for drying the stripped film.

3. In apparatus for stripping moving picture film, the combination of means for applying an aqueous softening medium to said film, means for removing the softened emulsion, and means for drying the treated film. 110

CARLETON ELLIS:
HARRY M. WEBER.
